UNITED STATES PATENT OFFICE.

SAMUEL KAYE, OF COLUMBUS, MISSISSIPPI.

BOTTLE REFRIGERATOR.

Application filed May 24, 1926. Serial No. 111,176.

My invention relates to improvements in refrigerators particularly adapted for the handling and dispensing of bottles such for instance as those containing carbonated beverages.

It is one of the objects of my invention to provide a refrigerator for dispensing carbonated beverage bottles which will provide means for containing a comparatively large 10 number of bottles with the minimum of size and with the minimum consumption of ice, which will permit the ready insertion of a warm bottle in and the removal of a cool bottle from the refrigerator and which will automatically drop the warm bottle into the 15 refrigerator chamber when said chamber is opened for the purpose of removing therefrom a cool bottle.

For the purpose of disclosing my invention 20 I have illustrated certain embodiments thereof in the accompanying drawings in which

Fig. 1 is a perspective view of a refrigerator embodying my invention;

Fig. 2 is a transverse sectional view thereof; 25 Fig. 3 is a partial longitudinal section thereof;

Fig. 4 is a detail plan showing the rear portion of the slides and the opening therein;

Fig. 5 is a detail section on the line 5—5 30 of Fig. 3;

Fig. 6 is a detail perspective of a portion of one of the slides, and

Fig. 7 is a perspective view of a modified means for guiding the slide members.

35 In one embodiment of my invention I provide a refrigerating container comprising a substantially rectangular sheet metal outer casing 1 provided with a bottom 2 of sheet metal which may be secured in position by 40 downwardly extending flanges 3 bolted or riveted to the bottom portion of the casing 1. Arranged within this casing and spaced apart therefrom is the container proper 4 which takes the form of a rectangular sheet metal 45 tank having its upper edges turned outwardly as at 5 and then upwardly as at 6 to provide a flange for bolting or riveting to the inner face of the casing 1. Interposed between the walls of the tank 4 and the walls of 50 the casing 1, including the bottom 2, is a suitable insulating material which may be formed of cork or any other desired material. The interior of the tank 4 is suitably divided to provide an ice chamber 7, which is centrally 55 disposed and a plurality of bottle channels 8

arranged on each side of the ice chamber and extending from front to rear.

In the structure illustrated I provide three such channels and to this end I provide a divider plate 9 substantially the same height as 60 the tank which plate at its ends is provided with inturned end spacer walls 10 the edges of which are turned parallel with the plate as at 11. This divider is placed in the tank with the two spacer end walls 10 facing toward the outer side wall of the tank whereby the space between the side wall of the tank and the spacer member 9 forms a channel for guiding the bottles. A second spacer member 65 exactly the same in construction as the member 9, with the exception that the end portions 10 face in the opposite direction, is arranged within the tank, being suitably spaced from the first member a distance sufficient to provide a second channel between 70 the two members. The end walls 10 of this second spacer member abut against a plate 12 arranged in the tank, which plate has a top portion 13 provided with a down turned flange 14 and this plate 12 forms one side 75 wall of the refrigerating chamber 7. For maintaining the plate in its proper relation at the bottom I provide a corrugated plate 15 placed on the bottom of the tank and having its edges engaging the bottom faces of the 80 two wall members 12. The spacer members 9 are also held against lateral deflection by means of shelf members 16 which comprise U shaped channels adapted when inverted to permit the insertion of comparatively large 85 bottles and when turned with the U portion up will provide a shelf for raising the shoulder bottles to a point where they may be reached from the top of the refrigerator. The tank is provided with a cover plate 17 having 90 downwardly extending outer flanges 18 which fit over the top edges of the outer casing 1 and which has a central opening at the point immediately over the ice chamber. The edges of the material surrounding this opening are turned downwardly to form flanges 18' and the down turned flanges 14 of the wall members 12 may be secured thereto whereby the 95 upper ends of the wall members 12 are maintained against displacement. This cover plate at its forward end and on each side of the ice chamber opening is provided with a 100 delivery opening 19 through which the bottles contained in the channels 8 may be removed, and at its rear end is provided with 105 110

openings 20 on either side of the ice opening through which the bottles may be inserted into the respective channels 8. These openings are normally closed by a plurality of 5 slide covers 21, one for each channel, which covers are preferably formed of sheet metal having its edges bent downwardly on each side to form runner flanges 22. The slides are reciprocal back and forth and for guiding 10 the slides and maintaining the same against lateral displacement each slide at its forward end is provided with a guide slot 23 through which extends a guide pin 24 threaded into a cross bar 25 fastened on the under face of the 15 cover plate 17. The slide openings and guide pins are covered by a suitable decorative raised panel 26 having at its rear end a lip or lug 27 taking into an opening in the top of the slide and secured at its forward end 20 by the handle 28 which is mounted on a pin secured in the slide and clamps down on the panel. The handle provides a means for suitably reciprocating the slide. The rear end of the slide is likewise guided by means of pins 25 29 threaded into a bracing plate 30 secured on the under face of the cover plate 17 and projecting through a slot 31 in the slide. This slot and pin is also covered by a raised panel 32 having side ears 33 which take into 30 openings in the slide cover 21 and are then bent transversely for holding the panel in position. Each of the slide covers 21 is of such a length relative to the top cover that it may be slid rearwardly and when slid to the 35 limit of its movement rearwardly will expose that portion of the opening 19 in the front end of the cover plate 17 immediately above the channel corresponding to the slide whereby a bottle may be removed through this opening. 40 This slide 21 at a point near its rear end is provided with an opening 34 of sufficient size to accommodate a bottle, which however, when the slide is in its forward position will rest, through the opening, on the cover plate 17. As the slide moves rearwardly it will 45 carrying the bottle with it until it is above the opening 20 in the cover plate 17 permitting the bottle to drop down into the channel corresponding to the slide. To prevent the 50 bottle from tilting and to aid in guiding the bottle downwardly through the opening 20 I provide a curved guard plate 35 coinciding with the rear portion of the opening 34 and this guard plate is extended downwardly 55 from the slide 21 into the channel forming a chute propeller 36 in front of which the bottle drops when projected through the opening 20 into the channel by the rearward reciprocation of the slide. The channel is adapted 60 to support and guide the bottles in a vertical position side by side in a row from front to back so that when a bottle drops into the rear portion of the channel through the opening 20 and in front of the propeller 36, the entire 65 row of bottles in the channel will be moved

forward by the forward or closing movement of the slide 21 whereby, when the slide is moved rearwardly, to an open position the first of the row of bottles will be immediately beneath the opening 19 and may be readily removed therefrom. 70

The ice opening in the cover plate 17 is normally closed by a suitable cover 37 and the tank is provided with a drain pipe 38, the drain opening 39 of which is sufficiently high 75 in the pipe to maintain the water level in the tank at a height sufficient to just expose or permit the upper portion of the neck of the bottles to be uncovered.

In order that the cooling liquid, which may 80 be merely the water melted from the ice, or a brine solution, may have free circulation throughout the tank, the dividing walls 9 for the channels are perforated and in order that the propellers 36 may not cause too great 85 agitation of the water as they are reciprocated in their channels, these propellers are likewise perforated.

A suitable shelf 40 for the support of display bottles and bottles to be placed in the 90 refrigerator may be provided at the back of the refrigerator, said shelf being provided with a back 41 and sides 42.

In Fig. 7 I have illustrated a modification 95 of the means for guiding the slides 21. As shown in this figure near the front of the cover plate and near the rear thereof I provide straps 43 and 44 beneath which the slides operate. These straps are provided with 100 downwardly extending projections or ears 45 which are interposed between the two outside slides and the middle slide whereby all of the 105 slides are suitably guided. Supported above and upon these slides are suitable channel guideways 46 which provide additional bottle storage space for bottles prior to insertion in the container.

I claim as my invention:

1. A cooler for bottles comprising a refrigerant container, a channel in said container 110 adapted to receive and guide a plurality of bottles side by side in an upright position, said channel being vertically accessible at each end, a reciprocal slide cover for said channel normally closing each end of the 115 channel against accessibility and arranged when reciprocated in one direction to render the channel accessible for the insertion of a bottle at one end and the removal of a bottle by the closing of the cover for moving the 120 bottles toward the removal end of the channel.

2. A cooler for bottles comprising a refrigerant container, a channel in said container adapted to receive and guide a plurality of bottles side by side in an upright position, said channel being vertically accessible at each end, a reciprocal slide cover for said channel normally closing each end of the channel against 125 accessibility and arranged when reciprocated 130

in one direction to render the channel accessible for the insertion of a bottle at one end of the channel and the removal of a bottle from the opposite end of the channel and a propeller mounted on said slide cover and movable therewith to move the bottles from the rear toward the removal end of the channel.

3. A cooler for bottles comprising a refrigerant container, a channel in said container adapted to receive and guide a plurality of bottles side by side in an upright position, a cover plate for said container having an opening into said channel at its front end and an opening into said channel at its rear end, a slide cover for said openings arranged when the slide is reciprocated rearwardly to expose both of said openings in the cover plate and when the slide is moved forwardly to close both of said openings in the cover plate and a propeller on said slide cover projecting into said channel and arranged to engage the bottles in said channel and move them toward the removal end of the channel.

25 4. A cooler for bottles comprising a refrigerant container, a channel in said container adapted to receive and guide a plurality of bottles side by side in an upright position, a cover plate for said channel having an opening communicating with the forward end of the channel and an opening communicating with the rear end of the channel, a slide cover for said openings arranged when moved to a retracted position to expose said openings to permit the insertion and removal of bottles into said channel, a propeller on said slide cover movable when the cover is moved to open position to a position to permit the insertion of a bottle in front thereof and when 40 the slide is moved to closed position engage and propel the bottles toward the removal end of the channel.

50 5. A cooler for bottles comprising a refrigerant container, a channel in said container adapted to receive and guide a plurality of bottles side by side in an upright position, a cover plate for said channel having an opening at the front end communicating with said channel and a second opening at the rear end communicating with said channel, a slide

cover for said openings having an opening at its rear end arranged to coincide with the opening in the cover plate when the slide cover is moved to uncover the forward opening and means operated by said slide cover for propelling the bottles in said channel toward the delivery end of the channel.

6. A cooler for bottles comprising a refrigerant container adapted to receive and guide a plurality of bottles side by side in an upright position, said channel being vertically accessible at each end, a reciprocal slide cover for said channel normally closing the channel against accessibility, arranged when reciprocated in one direction to render the channel accessible for the insertion of a bottle at one end and removal of a bottle from the opposite end and having a bottle engaging portion and arranged to engage and move a bottle to depositing position, when moved to render the channel accessible and means operated by the closing of the cover for moving the bottles toward the removal end of the channel.

7. A cooler for bottles comprising a refrigerant container having formed therein a centrally disposed ice chamber and a plurality of liquid communicating channels disposed on either side of said container each adapted to receive and guide a plurality of bottles side by side in an upright position and each being vertically accessible at each end, a reciprocal slide cover for each of said channels normally closing its channel against accessibility and operable independently of the other covers, said slide cover being arranged when reciprocated in one direction to render the channel accessible for the insertion of a bottle at one end and the removal of a bottle from the opposite end of its channel and means operated by the closing of each cover for moving the bottles of the corresponding channel toward the removal end of the channel.

In witness whereof I, SAMUEL KAYE, have hereunto set my hand at Columbus, Mississippi, this 21st day of May, A. D. one thousand nine hundred and twenty-six.

SAMUEL KAYE.
